(57) **CLAIM**

I claim the ornamental design for outdoor barbecue grill, as shown and described.

DESCRIPTION

FIG. 1 is a top perspective view of an outdoor barbecue grill showing my new design, with the lid in a closed position; FIG. 2 is a rear elevational view thereof, with the lid in the closed position;

FIG. 3 is a front elevational view thereof, with the lid in the closed position;

FIG. 4 is a left side elevational view thereof, with the lid in the closed position;

FIG. 5 is a right side elevational view thereof, with the lid in the closed position;

FIG. 6 is a top view thereof, with the lid in the closed position;

FIG. 7 is a top perspective view of outdoor barbecue grill with its lid in an open position;

FIG. 8 is a front elevational view thereof, with the lid in the open position;

FIG. 9 is a rear elevational view thereof, with the lid in the open position;

FIG. 10 is a left side elevational view thereof, with the lid in the open position;

FIG. 11 is a right side elevational view thereof, with the lid in the open position; and,

FIG. 12 is a top view thereof, with the lid in the open position.
